UNITED STATES PATENT OFFICE.

WALTER J. F. LIDDELL, OF CHARLOTTE, NORTH CAROLINA.

SAW-MILL SET-WORKS.

SPECIFICATION forming part of Letters Patent No. 292,330, dated January 22, 1884.

Application filed December 1, 1883. (No model.)

To all whom it may concern:

Be it known that I, WALTER J. F. LIDDELL, of Charlotte, county of Mecklenburg, State of North Carolina, have invented a new and useful Improvement in Set-Works for Saw-Mills, of which the following is a full, clear, and exact description, reference being had to the accompanying drawings, making part of this specification.

10 My invention relates to the means for adjusting the log or other material to be operated upon, and for indicating the relation to the saw, and adapting it to be cut into boards or strips of uniform thickness and without unnecessary waste.

It consists in the combination, with the adjustable knee or head-block, of a supplemental knee secured to one side of and adjustable with the main knee, and also independently thereof; also, in the combination, with the knee, of a rule or indicator applied to and moving with said knee, and a stationary index or pointer secured to the knee-guideway; in a novel construction and arrangement of the devices for effecting and regulating the adjustment of the head-block, and in certain details of construction and arrangement of parts, all as hereinafter explained.

In the accompanying drawings, Figure 1 represents in perspective a portion of a saw-mill carriage, showing one of the knees, its track or ways, and the mechanism for adjusting said knee. Fig. 2 is a side elevation of a portion of the same. Fig. 3 represents a horizontal section through the adjusting mechanism. Fig. 4 represents a vertical transverse section through a portion of the knee and its guideway, showing the indicator also in transverse section. Fig. 5 represents a section 40 through the slotted segmental rack, showing the adjustable stop and its retaining-clamp. Fig. 6 is a detail view of a portion of the adjusting-lever and dog or double pawl and spring connected therewith. Fig. 7 is a side elevation of the knee and its ways, with the adjusting mechanism removed to show more clearly the arrangement of the indicator. Fig. 8 is a vertical transverse section through the knee and its ways, showing an indicator on 45 each side of the knee; and Fig. 9 is a similar

view, looking from the rear, showing the manner of attaching the supplemental knee.

A A' represent longitudinal bars of the saw-mill-carriage frame B B', the flanged parallel rails forming the ways for one of the adjustable knees or head-blocks; and C, the knee adjustable thereon, said parts, except in particulars hereinafter explained, being of any usual or preferred form and arrangement. The knee C is provided on its lower face with a toothed longitudinal rib, c, pendent between the ways B B', and with which a pinion, d, on a shaft, D, engages for adjusting the knee, which, by preference, is made in T shape, (inverted,) with the edges of the cross-head C' grooved to 65 receive the flanges of rails B B', on which it moves. The cross-head is by preference extended over the rail B on one side, and provided in such extension C' with an inverted-T-shaped groove, c', open on the upper side, 70 adapting it to receive a supplemental knee, C', adjustable in said groove c'. This supplemental knee is similar in form to the knee C, and is made adjustable relatively to the latter, when required, for setting the log obliquely to 75 the head-block, or away from one of the knees thereof, for any purpose, by means of a screw-threaded rod or shaft, e, mounted in an arm or bracket, c'', on the side of the knee C, and engaging a burr or nut, e', fast in the rear face 80 of the supplemental knee C'. The shaft e is provided with collars e' e''—one on each side of the bearing-bracket c''—for preventing endwise movement of the shaft e, which may be operated by a hand-wheel, E, or other suitable 85 means for adjusting the supplemental knee as desired.

Upon one side of the knee, or of the vertical central rib on the upper face of the horizontal arm, is formed a pocket, F, for the reception of a rule or indicator, G, made by preference octagonal in form in cross-section, as shown; but it may be made flat, square, or in any other suitable form, its sides being marked to conform to the different thicknesses 95 of boards to be sawed. Thus, the side indicating that the material is to be cut into three-quarters of an inch in thickness will have its marks, say, one inch apart, allowing one-quarter inch for the cut of the saw, the side indi- 100

cating that the lumber is to be cut into inch-thick boards, showing the marks one inch and a quarter apart, the surplus quarter-inch, or whatever it may be in each case, representing 5 the width of the saw-kerf. The octagonal form will thus provide for eight different thicknesses, and obviate the necessity for a multiplication in the number of interchangeable rules or indicators, and by applying one 10 of these octagonal rules on each side of the central rib of the knee, as shown in Fig. 8, a sufficient number of changes may be provided for ordinary purposes without the necessity of substituting other indicator-rules.

15 The way B or B', either or both, has a pointer, g, secured to it, the upper end of which overhangs the upper face or side of the rule, which will be the one indicating the thickness of the boards into which the log is 20 to be sawed. This pointer may, if desired, be made in the form of a flat angular spring, its point overhanging the rule and preventing displacement of the latter, while at the same time permitting the rule to be withdrawn for 25 replacing it with another, or to be turned for bringing the desired side on top. The pocket for the reception of the rule is so arranged relatively to the knee as that when the rule is placed therein and brought into position with 30 one of its marks opposite or in line with the pointer, before the carriage is started, with a uniform subsequent adjustment of the knee or head-block conforming thereto, the log will cut into boards of uniform thickness, without 35 waste, and of the same thickness as the last board or strip remaining on the carriage. The outer wall of the pocket F is cut away at points indicated at f/f, to admit the thumb or fingers, facilitating the removal and insertion 40 of the rule G, as required. For effecting the adjustment of the knees, they are provided each with a pendent toothed flange, c, with which a pinion, d, on a horizontal shaft, engages, as above explained. This shaft D has 45 its bearings in the ways B and B', or in brackets thereon, and extends through all of such ways, and is provided with pinions for operating both or all of the knees of the head-block simultaneously when desired.

50 To one side of one of the flanged rails or ways B or B' is secured a segmental plate, H, slotted at h, to permit its adjustment, and secured to said rail by a bolt or bolts, i. The outer edge of this plate and the slots h and h' formed in it are in arcs of circles, of which the shaft D, passing through it, is the center, in such manner that in its adjustment the relation of said parts to said shaft is not disturbed.

55 The plate H is provided with a fixed spur or stop, h², which is adjusted with the plate, and a second adjustable stop, consisting of a perforated arm, J, pivoted on and adjustable around the shaft D as a center, is secured to the plate H, said arm at its outer end extending, like stop h², beyond the outer edge of the segment H. It is secured to the plate H by

means of a bolt, k, which passes through it, through the segmental slot h', and through a cam-faced washer or block, K, having a thumb-wheel or a lever, k', for facilitating its adjustment, and held in place on the bolt k by nuts k² k³, the latter serving as a jam-nut for holding the nut k² and cam-block at the desired adjustment. The block K is rectangular in form, elongated in one direction, in such manner that when turned crosswise relatively to the slot h' its ends will overhang the side walls of the slot; and said ends being made cam-faced, they serve to draw the arm J up snugly against the plate H and to lock it thereto. 80 Other means may be employed for securing the arms J to the plate, if preferred.

The plate H outside of the slot h' has a segment-rack, L, the teeth of which are so spaced as to represent eighths of an inch each in the 85 adjustment hereinafter described, and the adjacent face of the arm J is correspondingly toothed, so that when the two are clamped together, as above, accidental displacement of the arms or stop J is effectually prevented. 90 When the elongated block or button K is turned into line parallel with the slot h', it is sufficiently narrow to enter said slot, as indicated by dotted lines in Fig. 2, and so permit the disengagement of the teeth of arm J from 95 those of segment L, and the consequent ready adjustment of said arm or stop nearer to or farther from the fixed stop h², as desired.

To the shaft D is keyed a ratchet-disk, M, provided on its upper periphery with ninety-six teeth, of substantially the form (V shape) shown, each representing an eighth of an inch in the adjustment of the knees or head-block, and pinion d is provided with twelve teeth, this arrangement of the teeth serving to move 105 the head-block one foot at each revolution of the shaft D and its pinion d.

N is a lever pivoted on the shaft D, and provided with a double pawl, n, pivoted centrally to and crossing its side adjacent to the ratchet-disk M, just over the latter, in such manner that either end may be engaged with said disk, according to the direction in which it is desired to rotate the latter. This double pawl is connected with the lever N by the same pivotal bolt which unites a cross-head, D, to said lever, and the latter has rigidly connected with it a flat spring-arm, O', which extends upward by the side of the lever N, and serves, by its adjustment, to rock the cross-head for throwing either end of the double pawl into engagement with the ratchet-disk M or for releasing both ends, as desired.

The pawl is held in proper relation to the cross-head by springs n' n'', and the spring-arm O' is held in the desired relation to the lever N, for holding either end of the double pawl engaged with the ratchet-disk, by means of a pin, p, on the lever N, the adjustment of the lever to one side of said pin serving to 125 throw one arm of the pawl into engagement with the disk, and the adjustment of the arm 130

O' to the other side of said pin to throw the other arm of said pawl into engagement with the disk, while a central adjustment of the arm, allowing the pin to enter a slot or depression, o, in the lever, serves to hold both arms or pawls clear of the ratchet-disk.

The side of the rail B' adjacent to the disk M has an angular bracket, Q, secured to it, in the outer end of which is a pivotal pin or bolt, 10 q, supporting two pawls, q' q'', one slightly longer than the other, as indicated in Fig. 2, and provided with weighted heel-extensions or with springs adapted to hold them engaged with the teeth of the ratchet-disk, for holding 15 the latter when adjusted and preventing its accidental displacement.

The lever N has a lug or spur formed on its inner face adjacent to the plate H, and which projects within the vertical plane of and 20 between the stop h' and J, and serves to limit the throw of the lever, controlled by the relative adjustment or distance apart of said stops. Thus the teeth on the segment-rack L and the teeth of the ratchet-disk M represent each an 25 eighth of an inch in the adjustment of the head-block or knee, so that if the stop h and J be so adjusted as to permit a throw of the lever sufficient to move the ratchet-disk a distance equal to the space covered by eight of its teeth 30 the head-block or knee will be moved, under the arrangement of ratchet-teeth and pinion above described, a distance of one inch, which, after deducting one-quarter inch for the width of the saw-kerf, would, as will be apparent, 35 adapt the mechanism to set the material to be cut into strips or boards of three-quarters of an inch in thickness, while if the lever is set to move the disk the teeth and the boards will each be one inch thick.

40 Parts of the carriage and its attachments not particularly described may be constructed in any usual or preferred manner.

Having now described my invention, I claim as new—

45 1. In the set-works of a saw-mill, the adjustable knee provided with the grooved exten-

sion of its flange or base, in combination with the supplemental knee secured to and adjustable in said grooved flange, and means for adjusting the same, substantially as described. 50

2. The adjustable knee provided with a receptacle for an indicator-rule, in combination with an indicator secured to and moving with said knee, and a stationary pointer, arranged and operating substantially as described. 55

3. The adjustable knee provided upon each side of its longitudinal rib with a pocket for the reception of indicator-rules, in combination with the interchangeable polygonal indicator-rules, substantially as described. 60

4. The slotted segment-plate H, adjustable around the pinion-shaft as a center, and provided with the fixed stop, in combination with the adjustable stop, also pivoted upon and adjustable around the pinion-shaft as a center, 65 and the cam-faced block or lever for clamping said adjustable stop to the slotted segment H, substantially as described.

5. The plate or segment H, provided with the fixed stops h', slot h', and toothed segment- 70 rack L, in combination with the adjustable stop J, pivoted upon the pinion-shaft, and having teeth engaging said rack, and means for clamping said stop to said plate or segment, substantially as described. 75

6. The combination, with the lever for effecting the adjustment of the head-block or knee, of the centrally-pivoted double pawl and the cross-head supporting said pawl in operative position, both pivoted to said lever, the 80 socketed spring-arm rigidly secured to said cross-head for adjusting it, and the pin or spur on the lever for gaging the throw of said spring-arm and holding it at the desired adjustment, all substantially as described. 85

In testimony whereof I have hereunto set my hand this 24th day of November, A. D. 1883.

WALTER J. F. LIDDELL.
